FIXTURE WITH WALL RECEIVING PORTION

Alvin L. Lindstrom, Atlanta, Ga.

Application October 28, 1946, Serial No. 706,215

4 Claims. (Cl. 72—0.5)

1
This invention relates to improvements in building construction and particularly to an improved plaster joint for fixtures such as bath tubs, basins, cabinets, etc.

According to conventional practice, plumbing fixtures, such as bath tubs and basins, portions of which are set into the wall of a room, are provided with a horizontal flange or flanges for receiving the wall plaster, tile or the like in order to obtain a water tight joint. This conventional arrangement produces a sharp edge or corner between the horizontal ledge or flanged surface of the fixture and the vertical surface of the wall. Shrinkage, drying, or settling of one part relative to the other frequently causes the joint between the fixture and the wall to separate. Leakage of water into this space results in the accumulation of dirt and the deterioration of the wall adjacent the fixture, causing an unsanitary condition as well as an unsightly appearance of the joint between the fixture and the wall.

This conventional fixture construction also offers difficulty in the anchoring of the fixture firmly to the wall in a manner to avoid settling movement of the fixture relative to the wall. A problem is also encountered in adequately supporting the loads which the fixtures are required to bear, including the weight of water, objects and persons.

Also the conventional building construction is such that the wall covering is not rigidly anchored to the wall or partition, but rather is only affixed thereto, and is subject to both lateral and vertical movement which at times is greater or less than that of the wall framing to which the wall covering and the fixture is affixed.

Among the objects of the present invention are to provide an improved fixture having integral means for rigidly attaching the fixture to the wall of a building or to the wall and floor structure, which means also cooperate with the wall or floor covering to provide a permanent tight joint between the fixture and the wall or floor covering so that regardless of relative movements of the wall frame, the covering and the fixture, the covering cannot separate at its edge from the corresponding surface of the fixture to permit a crack to develop.

A further object resides in the provision of a housing fixture, such as a plumbing fixture or cabinet, having an integral wall cover receiving portion of simple and economical construction which will firmly unite the wall covering with the fixture.

2
A still further object resides in the provision of a plumbing fixture having along certain edges thereof integral flange portions by means of which the fixture may be rigidly attached to the adjacent walls or to the walls and floor of a room, which attaching means is also arranged to receive the adjoining edge portion of the wall or floor covering to maintain the covering permanently in intimate association with the fixture.

Other objects and advantages will become apparent as the description proceeds in conjunction with the accompanying drawings, wherein:

Fig. 1 is a fragmentary perspective of an improved fixture illustrative of the invention, and showing the manner of uniting the associated edge of the wall covering with a wall covering receiving portion provided on the fixture;

Fig. 2, a perspective of a modified form of wall covering receiving portion; and

Fig. 3, a fragmentary perspective of a further modification combining the forms of Figs. 1 and 2.

With continued reference to the drawing and particularly to Fig. 1, a fixture, such as a bath tub, basin or the like 10, is shown. This fixture has substantially vertical wall portions 11 and 12 which form portions of the complete fixture. Each of the wall portions 11 and 12 is provided at its upper edge with horizontal ledges 13 and 14. In the conventional construction, these ledges along the sides contacting the walls of the room, are either merely cut off along their outer edges or may, in some cases, be provided with integral stiffening beads of relatively small cross sectional area, which beads abut the structural members of the wall and receive on their upper surfaces the lower edges of the corresponding portions of the wall coverings such as plaster or tile. With such an arrangement, whenever the fixture is used, water washed up onto the horizontal ledges and against the lower edge of the wall covering comes in contact with the edge of the wall covering sufficiently to soften the bond between the wall covering and the upper surface of the ledges of the fixture. Under these conditions unsightly cracks develop between the upper surface of the fixture ledge and the edge of the wall covering resting thereon and any slight settling of the fixture widens such a crack and permits the water to flow under the edge of the wall covering, hastening the deterioration of the covering material where it joins the fixture.

In the improved arrangement shown in Fig. 1, the ledges 13 and 14 are curved upwardly at their

outer edges to provide corresponding curved channels 16 and 17 respectively and the upper edges of these curved portions are formed into respective flat horizontal flanges 18 and 19, each having a width substantially equal to the thickness of the wall covering 15 and having a flat horizontal upper surface upon which the adjoining edge of the wall covering rests. The flanges 18 and 19 extend beyond the outer sides of the curved channels to provide ledges or beads which may be received in suitable recesses provided in the structural members of the corresponding walls to resist settling movements of the fixture which would result in a separation of the flanges 18 and 19 from the corresponding edges of the wall covering. The curved channels 16 and 17 interposed between the upper surfaces of the ledges 13 and 14 and the bottom edges of the wall covering 15 prevent water from the fixture from coming in contact with the edge portions of the wall covering so that the bond between the wall covering and the flanges 18 and 19 is not destroyed and the edge portion of the wall covering is not deteriorated by constant wetting, and also provide a small amount of flexibility to compensate for the slight relative movements between the wall structural members, the wall covering and the fixtures. This construction will maintain a tight neat joint between the wall covering and the edges of the fixture in contact with the wall covering.

In the arrangement shown in Fig. 2, the fixture 20 is provided with vertical walls 21 and 22, and with integral horizontal ledges 23 and 24, respectively. These ledges are provided at their outer edges with upwardly extending vertical flange portions 25 and 26, respectively. The flange portion 25 is provided with a plurality of spaced apertures 27 preferably elongated horizontally and with a pair of inwardly and downwardly directed flanges 28 and 29, which are substantially parallel and disposed one above the other.

The flange 26 extending upwardly from the ledge 24 is provided with similar apertures 30 and inwardly and downwardly directed flanges 31 and 32.

The fixture may be firmly secured to the wall structure by means of fastening elements such as nails or screws inserted through some of the apertures 27 and 30. The wall covering material 33, such as plaster or a base material for tile, is then applied to the wall and extended over the inner sides of the flanged portion 25 and 26. Some of the covering material is pressed out through the apertures 27 and 30 and the downwardly hooked flange members 28, 29, 31 and 32 are embedded in the covering material, the covering material being extended downwardly to a seat on the upper surfaces of the ledges 23 and 24.

The fastening elements securing the flange portions 25 and 26 to the wall structure effectively prevent settling of the fixture relative to the wall and the engagement of the wall covering material with the apertures and the downwardly hooked flanges rigidly associates the covering material with the fixture in such a manner that the lower edge of the covering material cannot separate from the corresponding upper surfaces of the substantially horizontal ledges. With this arrangement, even though water is splashed upon the ledges and along the edge of the covering material, the bond between the covering material and the ledges is held so firmly that the water does not seep into any space between the wall covering material and the re-

ceptacle and thus any cracking of the wall covering material or separation of this material from the fixture is avoided.

The downwardly hooked flanges may be provided continuously along the flanged edge portion of the fixture as illustrated or may be provided as spaced hook members of any desired length. Flanges similar to the flanges 25 and 26 may also be provided along the edges of the fixture associated with the floor, particularly where a floor of plastic composition such as concrete is to be used and the joint thus provided between the fixture and the floor material will prevent any cracks from appearing along the joints between the fixture and the floor.

The downwardly and inwardly inclined shape of the flange members 28, 29, 31 and 32 enables these flange members to effectively transfer any separating force existing between the fixture and the wall covering to the wall covering so that this covering is held down firmly in place from the fixture and any separation between the fixture and the edges of the wall covering is precluded.

In the arrangement shown in Fig. 3, the side wall of the fixture or vertical fixture wall 34 is provided along its upper edge with the outwardly extending generally horizontal ledge portion 35, the outer edge of which is bent up as indicated at 36 to form a curved channel 37 similar to the channel 16 of Fig. 1. The top of the bent up portion 36 carries an integral angle member, generally indicated at 38, of L-shaped cross section having a substantially vertical leg 39 and a substantially horizontal leg 40. The horizontal leg 40 is provided with a flat upper surface providing a base or support which receives the corresponding edge of the wall covering material 41 and supports this edge of the wall covering material at a height above the ledge 35 equal to the height of the curved channel 37 thereby rendering the bond between the fixture and the edge of the wall material substantially dry at all times.

The vertical leg 39 is provided with spaced apertures 42 similar to the apertures 27 and 30 of Fig. 2 and with inwardly and downwardly extending flange portions 43 and 44.

As indicated above in the description of the arrangement shown in Fig. 2, fastening elements, such as nails or screws, may be driven through some of the apertures 42 into the wall structure to firmly unite the fixture with the wall of the room in which the fixture is installed. Some of the plastic wall covering material 41 is pressed through the apertures 42 to provide a key lock between the plaster 41 and the fixture flange 38 and the flange portions 43 and 44 are also deeply embedded in the plaster to transmit any settling action of the fixture to the plaster, thereby precluding any separation between the edge of the plaster wall covering and the upper surface of flange leg 40.

As stated above, the wall covering 41 may be a conventional plaster covering or may be any other desired form of wall covering, such as a plastic base for tile as indicated at 45 in Fig. 3. When tile is applied to the surface of the covering the edges of the tiles in contact with the fixture will be held firmly in place on the adjacent fixture surface so that there will be no tendency to break the bond originally provided between the tiles and the fixture and no crack between the tiles and fixture will appear, since separation between the tiles and fixture is definitely precluded by the improved construction, which retains the wall

covering material firmly in position relative to the fixture.

The improved construction has been illustrated as applied to a bath tub or a basin and to the portions of such plumbing fixtures as are in contact with the walls of the room in which the fixture is installed. As stated above, the improved joint bonding arrangement may also be applied to the portions of such fixtures in contact with the floor of the room in which the fixture is installed and may also be applied to other fixtures or devices, such as cabinets and mirrors, which are set into the wall covering material.

It will be obvious to those skilled in the art that various changes may be made in the invention without departing from the spirit and scope thereof and therefore the invention is not limited by that which is shown in the drawings and described in the specification but only as indicated in the appended claims.

What is claimed is:

1. A fixture having an upright side wall adapted to be positioned in contact with a vertical wall comprising a horizontally disposed ledge extending along the upright side wall, the inner edge of the ledge sloping downwardly from the ledge to the side wall, the outer edge of the ledge extending in the same general direction as the side wall and having fixedly secured thereto a horizontally disposed elongated upstanding flange, and a horizontally disposed angle member positioned above said upstanding flange with one leg extending horizontally and the other leg extending vertically, said one leg intermediate its edges abutting the upper edge of said flange and secured thereto, the free edge of said one leg extending inwardly beyond said flange, the other leg of said angle member extending upwardly, said ledge, flange and said one leg of said angle member being adapted to cause water to run off.

2. A fixture having an upright side wall adapted to be positioned in contact with a vertical wall comprising a horizontally disposed ledge extending along the upright side wall, the inner edge of the ledge sloping downwardly from the ledge to the side wall, the outer edge of the ledge extending in the same general direction as the side wall and having fixedly secured thereto a horizontally disposed elongated upstanding imperforate flange, and a horizontally disposed elongated angle member positioned above said upstanding flange with one leg extending horizontally and the other leg extending vertically, said one leg abutting the upper edge of said flange and having its free edge projecting inwardly beyond said flange toward said side wall, a flange portion positioned on the inner face of said other leg projecting inwardly therefrom, said flange portion serving to key plaster to said fixture.

3. A fixture having an upright side wall adapted to be positioned in contact with a vertical wall comprising a horizontally disposed ledge extending along the upright side wall, the inner edge of said ledge sloping downwardly from the ledge to the side wall, the outer edge of the ledge extending in the same general direction as the side wall and having fixedly secured thereto a horizontally disposed elongated upstanding flange, a horizontally disposed elongated angle member positioned above said upstanding flange with one leg extending horizontally and the other leg extending vertically, said one leg intermediate its edges abutting the upper edge of said flange and secured thereto, the free edge of said one leg projecting inwardly beyond said flange, the other leg of said angle member extending upwardly, a first flange portion positioned at the upper end of said other leg of said angle member sloping downwardly and inwardly therefrom secured to said other leg, and a second flange portion positioned on the inner face of said other leg intermediate the edges thereof and sloping downwardly and inwardly therefrom, said flange portions serving to key plaster to said fixture.
4. A fixture having an upright side wall adapted to be positioned in contact with a vertical wall comprising a horizontally disposed ledge extending along the upright side wall, the inner edge of said ledge sloping downwardly from the ledge to the side wall, the outer edge of the ledge extending in the same general direction as the side wall and having fixedly secured thereto an imperforate flange, a horizontally disposed angle member positioned above said upstanding flange with one leg extending horizontally and the other leg extending vertically, said one leg abutting the upper edge of said flange and having its free edge projecting inwardly beyond said flange toward said side wall, a flange portion positioned on the inner face of said other leg projecting inwardly therefrom, said flange portion serving to key plaster to said fixture.
